DESIGN.

A. HEALD.

Carpets.

No. 7,439.

Patented May 19, 1874.

Witnessed, G. H. Gifford

Thos. M. Smith

UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WILLIAM McCALLUM, OF SAME PLACE.

DESIGN FOR CARPET.

Specification forming part of Design No. 7,439, dated May 19, 1874; application filed May 8, 1874.
[Term of Patent 3½ years]

CASE T.

To all whom it may concern:

Be it known that I, ALFRED HEALD, of Philadelphia, Pennsylvania, have invented a Design for a Carpet-Pattern, of which the following is a specification:

The figure in the accompanying drawing clearly represents my design for a carpet-pattern.

The pattern is crossed diagonally in opposite directions by bands A A', at right angles to each other, and representing trunks of trees, the said bands inclosing square or diamond-shaped spaces, in each of which is a group of flowers, leaves, and stems, B, arranged in a

manner so clearly shown in the drawing as to render minute description unnecessary.

Irrespective of the colors employed, I claim—

The design for the crossed bands A A' and groups of flowers, leaves, and stems B, all arranged as described, and as shown in the drawing.

In testimony whereof I have signed my name to this specification in the presence of two subscribing witnesses.

ALFRED HEALD.

Witnesses:

W.M. A. STEEL,
E. H. ECKFELDT.
